BEATRICE P. SCOTT, OF MARBLEHEAD, MASSACHUSETTS

REPRODUCING PROCESS

Application filed August 28, 1928. Serial No. 302,573.

This invention relates to a process for producing upon one surface, characters corresponding to like characters upon another surface.

5 An object of this novel process constituting the subject matter of this invention is primarily to afford amusement and entertainment for young and old.

A further object is to provide means for 10 cheaply and rapidly transferring printed matter from paper to show windows, metal and other surfaces, so as to provide a means of advertising display which will neither damage the original nor the surface to which 15 the copy is applied.

A still further object is to provide means for transferring printed matter to other surfaces whereby the condition of the copy will be such that it may be readily erased or 20 made permanent at will, as desired.

Other objects and advantages will be readily understood from the following description and the accompanying drawing.

The drawing illustrates the apparatus of 25 the invention with the fingers showing the successive steps in the use thereof.

Fig. 1 is an exploded view of the apparatus used in carrying out the invention and showing the first step in the process.

30 Fig. 2 shows the parts combined ready for the copying operation.

Fig. 3 illustrates the transferring operation, while

Fig. 4 shows the completed, transferred 35 picture.

Referring in detail to the drawing, the apparatus used for practising the invention and shown in Figure 1 consists of a textile screen-like member 1, such as a piece of 40 bolting cloth, muslin or the like. For convenience in use it is secured upon one side of a frame 2 preferably rectangular in shape and made of wood. The bolting cloth when attached makes, as it were, a hollow box, 45 the wooden frame constituting the sides and ends, and the cloth the bottom of the box. Another frame 3 may be provided, which, however serves merely as a guiding or limiting frame for retaining the printed matter 50 to be copied. This frame is not absolutely

necessary but is a convenient means for preventing shifting of frame 1 during use. A piece of printed matter to be copied is indicated by 4 and shown as a newspaper cartoon or advertisement which it is desired to 55 transfer to another surface. The printed matter may be cut to fit snugly within frame 3, or else the frame 3 may simply be set over the newspaper or the like so as to encompass desired portions thereof.

The first step in the process of reproducing the character designated as 5 on the piece of newspaper 4 is to reproduce the character on the bolting cloth. This step is carried out by placing the frame 2, bolting 60 cloth side down upon the newspaper, using the guide frame 3 if desired, as illustrated in Fig. 2, and with a powder puff or piece of flannel represented as 6 rubbing a dry powder over the upper surface of the cloth 65 within the box. The powder may be corn-starch, talcum powder, or flour, for example. The powder may be first dusted over the muslin or bolting cloth or it may be placed upon the powder puff and then rubbed over 70 the said cloth. In this rubbing, it has been found that the powder tends to adhere to that portion of the paper beneath the bolting cloth which is defined by the printed character, but that no adherence occurs in the 75 unprinted parts. It has been found best to supplement the first rubbing with a powder puff with a subsequent rubbing with a piece of chamois. This very effectively rubs the powder into the interstices of the cloth where 80 it remains in those regions of the cloth above the unprinted part of the paper; but in the part of the cloth overlying the printed character, the powder has passed through the interstices and adhered to the underlying 85 printed character.

The frame 2 is then raised from the paper and when viewed by looking through the cloth it is found to contain a perfect reproduction 90 of the printed character, the bolting cloth being rendered opaque by the powder in the meshes everywhere but in the region corresponding to the printed character. It will have the appearance indicated in Fig. 3. It 95 has been found that the powder is very effective.

tively held by the bolting cloth. The image-bearing frame so made may be shipped and even roughly handled without obliterating the image.

5 The next step consists in the reproduction of the character upon or its transfer to another surface. Such a surface should be polished metal as nickel or silver plate. Also glass, celluloid, hard rubber, lacquered and 10 varnished surfaces and some painted surfaces will also receive the reproduction, as will also black or colored glazed paper, or the like.

15 The image-bearing cloth is then placed down upon this surface and while firmly held the image is reproduced upon the receiving surface by pulling a squeegee 15, a piece of rubber or card board over the cloth holding the design. The result can also be obtained 20 by placing a piece of plain paper over the design and rubbing the paper.

This pulling or rubbing loosens and forces the powder from the bolting cloth upon the receiving surface, covering the surface except 25 for a region corresponding to the transparent part of the cloth and, of course, corresponding to the original printed character. Upon the removal of the cloth, the powder, which has been rubbed through, gives an outline defining 30 a true representation of the original printed character.

The reproduction may be precisely like the original, if the original be black and white, by using a black glossy paper as suggested 35 by 7 in Figures 3 and 4, or if on glass by painting with black paint the underneath surface of the glass. Various beautiful results may be had by using colored powders.

40 A squeegee has been mentioned as an implement for reproducing the figures upon the polished surface. It is not intended to limit the invention to any particular implement. It has been found that the transference may be effected by merely drawing the end of the 45 finger over the cloth. The squeegee is a convenient implement and is considered at present perhaps the best. The picture thus reproduced might be supposed to adhere so feebly that the glass or paper bearing the 50 reproduction could not be handled except with great care. The adherence, however, is so perfect, that the reproduction can be carelessly handled without danger of injury.

The image may be instantly removed by 55 wiping the surface with the hand or cloth, and the surface is then ready for another transference.

The image may be made permanent by spraying with a thin coat of shellac and alcohol or a suitable water-soluble size.

The dry powder is of course chemically inert and no injury results even if the reproductions are made upon window glass or polished surfaces as of furniture by children.

85 In addition to affording amusement when

used as described, the transfer device has a value for advertising purposes. With such a process it will be seen that attractive advertisements, cartoons, or the like, may be readily reproduced by store-keepers or salesmen 70 upon store windows or show-cases.

It will of course be understood that the characters reproduced may be pictures, figures, letters or any printed matter. I have found that the best results are obtained by 75 working with unglazed newsprint paper, from any one printed portion of which a number of reproductions may be easily made.

This invention is not limited to the transference of characters printed on newspaper. 80 Any material printed in printer's ink may be copied. Image-carriers may be made by first printing the desired design on paper and then preparing the stencil as already described. This opens the way for originally producing 85 and thereafter reproducing a design.

Should it be desired to make such an image-bearing cloth permanent a suitable powder may be selected such that when the image-carrier is formed the powder may be hardened 90 by the use of a suitable liquid applied to the cloth. From such a permanent carrier many reproductions may be made.

A permanent image-carrier as described above will be particularly useful for advertising purposes. It can be made more economically than similar carriers made by other methods. The reproductions may then be made in indefinite numbers with a dry powder. Such reproductions can be easily removed by wiping the powder from the surface as hereinbefore described.

I claim:

1. A process for reproducing characters formed of printer's ink consisting in placing 105 a screen over the characters to be reproduced, rubbing a dry powder into said screen to form in the interstices thereof a copy of the original in powder-image form and thereafter placing said image-carrying screen upon a 110 receiving surface and rubbing the powder contained in said screen from the screen and upon the surface.

2. A process for reproducing characters from a surface having the characters thereon formed by printer's ink consisting in placing 115 a screen-like textile material over said characters and then rubbing a dry powder into said screen, removing said screen, placing the screen upon a receiving surface and 120 rubbing the enmeshed powder through the screen and upon the receiving surface.

3. A process for reproducing characters from printer's ink consisting in placing a fine mesh textile screen upon said characters, rubbing a fine powder over said screen and above 125 the printed and unprinted region, again rubbing the powder into said screen with a chamois or the like, removing the screen from the printed surface and placing it over a receiv- 130

ing surface, and rubbing the powder remaining in the screen with a squeegee or the like through the screen and upon the second surface.

- 5 4. A process of conditioning an image carrier adapted for transferring printer's ink characters from one surface to another consisting in placing a fine mesh cloth over a surface containing said printer's ink character and rubbing a dry powder over said cloth into the interstices of the cloth and throughout the region over the unprinted parts and through the cloth and upon the printed character in the region over the printed part.
- 10 5. A process for reproducing a character of printer's ink consisting in placing a screen over the character, filling the interstices of the screen around the outline of the character with a dry powder, placing the screen over a 20 receiving surface and forcing the powder from the screen to that surface.
